United States Patent

Des. 235,791
Patented July 8, 1975

235,791

WEIGHTED INSERTS FOR GOLF CLUBS OR SIMILAR ARTICLES

Ronald A. Kurtz, Englewood, and Henry H. Utzinger,
Ridgefield, N.J., assignors to Kulite Tungsten Corpo-
ration, Ridgefield, N.J.

Filed Feb. 26, 1973, Ser. No. 335,698

Term of patent 14 years

Int. Cl. D21—02

U.S. Cl. D34—5 GC

Fig. 1.

Fig. 2.

Fig. 3.

Fig. 5.

FIG. 1 is a top view of an insert for golf clubs or similar articles according to our design;

FIG. 2 is a side elevational view of the insert for golf clubs or similar articles of FIG. 1;

FIG. 3 is a bottom view of the insert for golf clubs or similar articles of FIG. 1;

FIG. 4 is a perspective view of the insert for golf clubs of FIG. 1; and

FIG. 5 is a bottom view of an alternate embodiment of an insert for golf clubs according to our design.

We claim:

The ornamental design for weighted inserts for golf clubs or similar articles, substantially as shown.
